UNITED STATES PATENT OFFICE.

HENRY W. PELL, OF ROME, NEW YORK.

DROP-PERCH FOR VEHICLES.

SPECIFICATION forming part of Letters Patent No. 314,714, dated March 31, 1885.

Application filed July 28, 1884. (No model.)

To all whom it may concern:

Be it known that I, HENRY W. PELL, of Rome, in the county of Oneida, in the State of New York, have invented new and useful 5 Improvements in Drop-Perch Connections, of which the following, taken in connection with the accompanying drawings, is a full, clear, and exact description.

This invention consists in improved means 10 for firmly and securely connecting two perches to the head-block of a vehicle, as hereinafter fully described, and specifically set forth in the claims.

The invention is clearly illustrated in the 15 annexed drawings, wherein Figure I is a top view of the forward end of two perches and their connection with the head-block and spring mounted thereon. Fig. II is a transverse section on line $x x$, Fig. I, with a portion 20 of the side of the coupling-arm broken away to show the concavity of said arm and the extension of the perch into the same. Figs. III and IV illustrate modifications in the detail construction and combination of the 25 aforesaid parts. Figs. V, VI, and VII are perspective views showing in detail the modifications of the construction of the transom-plate and perch-couplings. Fig. VIII is a transverse section on line $y y$, Fig. III, and 30 Fig. IX is a longitudinal section on line $z z$, Fig. I.

Similar letters of reference indicate corresponding parts.

H represents the head-block, S the spring 35 mounted thereon, and P P denote two perches connected with the head-block by the following instrumentalities: The usual transom-plate, a , which is secured to the under side of the head-block has integral with it two rearwardly-projecting arms, $b b$, which are deflected downward and extended under the end 40 of the perch P, as shown in Figs. II, III, and IV of the drawings. Over each of the arms $b b$ is a brace, c , the rear end of which lies on 45 top of the perch, and is secured thereto by bolts passing vertically through said parts and through the arms $b b$. The forward end of the brace is extended across the transom-plate a and countersunk in the under side of the head-block, as shown in Fig. IX of the 50 drawings, and the central or intermediate portion of the brace is formed concavo-convex

and deflected downward, corresponding to the arm b , and lies with its edges contiguous to the top of said arm. The concavo-convex 55 form of the brace c is easily produced from a comparatively light bar by means of a drop-press with suitable dies, and said form imparts rigidity to the brace and serves as a socket for the reception of the end of the perch, 60 as illustrated in Fig. II of the drawings. The embrace of the end of the perch by the brace c obviates the danger of splitting the perch. The concavo-convex portion of the brace terminates with a shoulder, s , by which it abuts 65 against the rear of the head-block. The said brace and transom-plate a have in common their attachment to the head-block. Said attachment I prefer to make by means of the clip C, which embraces the spring S and head-block, and has its ends extended through the brace and transom-plate, and provided underneath the latter with nuts $n n$, by which to clamp the parts together. If it is desired to fasten the spring to the head-block by a single clip at the center thereof, a bolt may be 70 extended vertically through the head-block and through the brace and transom-plate, as shown in Fig. IV of the drawings. The connection of the perch with the head-block can 75 be re-enforced by shoulders s' either on the front edge of the transom-plate, as represented in Fig. IV of the drawings, or on the forward end of the braces, as shown in Fig. V of the drawings, which shoulders abut against 80 the front of the head-block, as illustrated in Figs. II and III of the drawings.

It will be observed that in every instance the brace c is extended across the transom-plate, and has in common with it the attachment 85 to the head-block, and is countersunk in the head-block, and thus securely retained in its position over the arms $b b$ of the transom-plate.

Having described my invention, what I 90 claim as new is—

1. In combination with the head-block H and perches P P, the transom-plate a , having the arms $b b$ integral with it and extended under the perches, and the braces $c c$ on top of the perches and extended across the top of the transom-plate and countersunk in the under side of the head-block, substantially as described and shown.

2. In combination with the head-block H, perches P P, and the transom-plate a, formed with the arms b b, the braces c on top of the arms b b, and extended between and across the
5 transom-plate and head-block and shouldered against the side of the head-block, substantially as shown and set forth.

In testimony whereof I have hereunto signed

my name and affixed my seal, in the presence of two attesting witnesses, at Syracuse, in the county of Onondaga, in the State of New York, this 9th day of June, 1884.

HENRY W. PELL. [L. S.]
